UNITED STATES PATENT OFFICE.

WILLIAM R. GEESEY, OF ALTOONA, PENNSYLVANIA.

VESTIBULE-CURTAIN FASTENER.

1,074,944.

Specification of Letters Patent.

Patented Oct. 7, 1913.

Application filed April 2, 1912. Serial No. 688,109.

To all whom it may concern:

Be it known that I, WILLIAM R. GEESEY, a citizen of the United States, residing at Altoona, in the county of Blair and State 5 of Pennsylvania, have invented certain new and useful Improvements in Vestibule-Curtain Fasteners, of which the following is a specification.

This invention relates to an improvement 10 in car vestibule curtain fastening devices, and contemplates a device by which a vestibule curtain, that is mounted upon a spring actuated roller secured to the door frame of one car, is, after being pulled across the face 15 of the diaphragm and face plates between the cars, secured to the door frame of the next car so that the fastening device is not affected by the usual stresses put upon the curtain when the cars are passing around 20 curves. However, the curtain is adapted to be automatically released should the cars become uncoupled purposely or by accident.

To this end the invention contemplates 25 a device, the body or casing of which is adapted to be slidably fastened to a base plate which may be secured to the door frame of a car in such a position, that the loop attached to the free end of the curtain 30 may be readily held thereby in position when the cars are coupled together, but can be automatically released to prevent damage to the curtain should the cars separate.

With these and many other objects in 35 view, which will more readily appear, as the nature of the invention is better understood, the same resides in the novel construction, combination and arrangement of parts, hereinafter more fully pointed out, 40 illustrated and claimed.

The essential features of the invention involved in carrying out the objects above indicated are susceptible to a wide range of structural modification without departing 45 from the spirit or scope of the invention, but a preferred and practical embodiment of the invention is shown in the accompanying drawings, in which:—

Figure 1, is a longitudinal sectional view 50 taken through the center of my improved vestibule curtain fastening device showing in dotted lines a portion of the vestibule curtain, the curtain loop as well as a portion of the door frame of the car. Fig. 2 55 is a plan view of the curtain fastening de-

vice and curtain loop shown in Fig. 1. Fig. 3 is a sectional view taken on the line 3—3 of Fig. 1. Fig. 4, is a longitudinal sectional view of the combined spring casing and curtain loop strike. Figs. 5 and 6 are end 60 elevations of the parts shown in Fig. 4 of the drawings. Fig. 7 is a plan view of the combined spring stop and casing guide. Figs. 8 and 9 are edge views of the parts shown in Fig. 7. Fig. 10 is a cross sec- 65 tional view taken on the line 10—10 of Fig. 7, and shows very clearly the portion forming the curtain loop keeper. Fig. 11 shows a detail of the spring used to actuate the combined spring casing and curtain 70 loop strike. Fig. 12 is a sectional view taken on the line 2—2 of Fig. 4.

Like reference numerals designate corresponding parts throughout the several figures of the drawings.

In carrying out this invention, no change is contemplated in the usual door frame to which the curtain fastening device is attached, nor is it necessary to make any change in the curtain or the curtain loop.

With particular reference to the several views of the drawings the improved fastening embodies a combined spring casing and vestibule curtain loop designated in its entirety by the numeral 10, and comprises in 85 detail a hollow semi-cylindrical spring casing member 11, having formed on the interior of one of its end walls 12, a hollow boss 13. The assembling pin 14 passes through the boss 13 and its threaded end 15 enters 90 the threaded socket 16, in the opposite end wall 17 of the casing 11. The end wall 12 is also provided with a pendent guide projection 18, which is substantially T shape in design and the arms of which are designated 95 19. The said arms 19 are adapted to slide in suitable guides 20 which are formed in the underside of the base member 21.

The base member 21, is provided with an outwardly projecting collar 22, formed from 100 the upstanding lug 23. The said collar 22 permits the bolt or pin 14 to pass therethrough so that when the spring 24 is in place, as shown in Fig. 1 of the drawings, and the pin 14 screwed into position, the 105 inside lip 25 of the strike 26 approaches the outwardly projecting keeper shoulder 27 of the base member 21, thus, forming a resilient keeper member. The entrance of the 110 curtain loop holder 28 to the curtain fastener

is facilitated by the beveled sides 33 and 34 against which the loop strikes before entering the loop holding portion of the latch designated as 35.

5 From the foregoing it will be readily apparent that the curtain loop 28, when occupying the position, shown in Fig. 1 of the drawings, will by virtue of the spring 24, keep the face 29 against the face 30 and so 10 remain until the tension on the vestibule curtain 31 exceeds the resistance offered by the spring; whereupon the inside lip 25, of the strike 26, will move outward thereby releasing the curtain loop 28. It will be obvious also that the curtain loop can be otherwise released by compressing the spring with one hand and pulling the loop out with the other. Or by simply compressing the spring by pressure on the wall 12, and the 15 force of the rerolling of the curtain and roller on the opposite car, will pull the loop 28 out of the keeper.

From the foregoing description, together with the drawings it is thought that the 25 many advantages of my improved vestibule curtain fastening will be apparent, and

What I claim and desire to secure by Letters Patent, is:—

30 1. A vestibule curtain fastener, comprising a base member having a guideway and an upstanding lug provided with an opening, a casing member having end walls one of which has a hole, and the other of which has a screw threaded socket, a hook having a 35 shoulder formed integral with the casing, a pendent guide projection also carried by the casing member and adapted to slide in the guideway in the base member, a pin adapted to hold the casing and base members slid-

ably together, and a spring for holding the 40 said sections in operative relation.

2. A vestibule curtain fastener, comprising a base member and a casing member, said base member having a guideway, an upstanding lug having an opening, and further provided with an outwardly projecting keeper shoulder, the said casing member having end walls one of which is provided with a hole and the other with a threaded 45 socket, a pendent guide member on the casing adapted to slide in the guideway, a shouldered hook integral with the casing and co-operating with the keeper shoulder on the base member to form a closure, a pin adapted to be screwed into the threaded socket on 50 the casing member and slidably pass through the opening on the lug on the base member to slidably hold the base and casing members together, and spring means for cushioning the sliding members. 60

3. A vestibule curtain fastener, comprising a base member having a guideway and provided with attaching means, a fastening receiving lug on said member; a fastening element, a casing member including a hook, and provided with guide means, said casing member adapted to be detachably and slidably connected to the base member by said fastening element being inserted through the 65 said fastening receiving lug, and spring means for holding the casing section in an operative position. 70

In testimony whereof I affix my signature in presence of two witnesses:

WILLIAM R. GEESEY.
